UNITED STATES PATENT OFFICE

159,183

EXTENSIBLE BAND FOR A WATCH BRACELET OR SIMILAR ARTICLE

Allen Benjamin, Chicago, Ill.

Application March 11, 1949, Serial No. 1,351

Term of patent 7 years

(CL D45—4)

To all whom it may concern:

Be it known that I, Allen Benjamin, a citizen of the United States, residing at Chicago, county of Cook, and State of Illinois, have invented a new, original, and ornamental Design for an Extensible Band for a Watch bracelet or Similar Article, of which the following is a specification, reference being had to the accompanying drawing, forming a part thereof, in which:

Figure 1 is a plan view of an extensible band for a watch bracelet, or similar article, embodying my new design;

Figure 2 is an enlarged partial plan view;

Figure 3 is an end view; and

Figure 4 is a partial sectional view on the line 4—4 of Figure 2.

I claim:

The ornamental design for an extensible band for a watch bracelet or similar article, as shown.

ALLEN BENJAMIN.
